US00D897998S

(12) **United States Design Patent** (10) **Patent No.:** **US D897,998 S**
Ma (45) **Date of Patent:** **** Oct. 6, 2020**

(54) **EARPHONES**

(71) Applicant: **SHENZHEN NA YIN TECHNOLOGY CO., LTD.**, Shenzhen (CN)

(72) Inventor: **Shaowu Ma**, Shenzhen (CN)

(73) Assignee: **SHENZHEN NA YIN TECHNOLOGY CO., LTD.**, Shenzhen (CN)

(**) Term: **15 Years**

(21) Appl. No.: **29/737,817**

(22) Filed: **Jun. 11, 2020**

(30) **Foreign Application Priority Data**

May 29, 2020 (CN) 2020 3 0262012

(51) **LOC (12) Cl.** **14-01**

(52) **U.S. Cl.**

USPC **D14/223**

(58) **Field of Classification Search**

USPC D14/223, 205; D24/174; 128/864, 865, 128/866; 381/380, 381, 374; 455/90.3, 455/575.1, 569.1

Primary Examiner — Paula Allen Greene

(57) **CLAIM**

The ornamental design for earphones, as shown and described.

DESCRIPTION

FIG. 1 is a perspective view of earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and

FIG. 9 is a perspective view of the earphones where the earphones are received in a charging case;

FIG. 10 is an enlarged view of portion 10 shown in FIG. 1; and,

FIG. 11 is an enlarged view of portion 11 shown in FIG. 3. The broken lines in the drawings depict portions of the earphones that form no part of the claimed design.

1 Claim, 11 Drawing Sheets
